(57) **CLAIM**

The ornamental design for a beverage press, as shown and described.

DESCRIPTION

FIG. 1 is a front view of a beverage press showing our new design;

FIG. 2 is a left side view thereof,

FIG. 3 is a right side view thereof,

FIG. 4 is a rear view thereof,

FIG. 5 is a top view thereof,

FIG. 6 is a bottom view thereof,

FIG. 7 is top, right-side perspective view thereof; and,

FIG. 8 is top, left-side perspective view thereof.

The broken lines are included for the purpose of illustrating the portions of the beverage press that form no part of the claimed design.

1 Claim, 7 Drawing Sheets
